CHAIR BASE

Rudolph Birr, Lombard, Ill., assignor to Precision Metal Workers, Chicago, Ill., a corporation of Illinois

Application November 8, 1946, Serial No. 708,755

3 Claims. (Cl. 248—194)

1

The present invention relates to improvements in base structures for standards adapted to support various articles of furniture and other fixtures.

The primary objects of the present invention are to provide a base structure which can be made at low cost by inexpensive and expeditious manufacturing methods, and which is simple, rugged and durable in construction.

Other objects and advantages will become apparent as the description proceeds.

In the accompanying drawings:

Fig. 1 is a fragmentary side view of a chair base embodying the features of the present invention;

Fig. 2 is a fragmentary horizontal sectional view taken along line 2—2 of Fig. 1;

Figs. 3 and 4 are fragmentary vertical sectional views taken respectively along lines 3—3 and 4—4 of Figs. 2 and 1;

Fig. 5 is a perspective view of the central head of the base structure shown at an intermediate stage in the course of manufacture.

Referring more particularly to the drawings, the base structure, constituting the exemplary embodiment of the invention, although adapted for various kinds of fixtures, is particularly suited for use as a posture chair base. In the specific form shown, the chair base comprises a central head 10 which is adapted to interconnect a plurality of supporting legs 11, and which has a vertical guide sleeve 12 opening axially therethrough for adjustably receiving and supporting a depending standard 13 adapted to be attached at the upper end to the underside of the chair seat (not shown).

The central head 10 with the axial sleeve 12 constitutes a unit of complex shape which if produced as a metal casting would present difficulties in manufacture resulting in considerably increased cost. In the present instance, the head 10 is constructed of simple standard parts, such as flat metal stock and metal tubes which are cut and shaped in simple stamping operations, and which are then suitably connected, as by riveting and welding, into an integral structure. Thus, the head 10 comprises two like circular plates 14 with central openings 15 which may be stamped or cut in any suitable manner out of a flat metal sheet. The flat plates are then conveniently formed in a stamping operation to the desired shape. In the present instance, each plate is formed with a plurality of uniformly-spaced semi-cylindrical protuberances 16 struck outwardly from one side of the normal plane and

2

extending radially from the opening 15 to the outer periphery. The preformed plates 14 are rigidly secured together, as by means of rivets 17 in peripheral registration and flat face to face engagement, with their protuberances 16 disposed in opposed relation to define a plurality of cylindrical radial sockets 18 for anchoring the legs 11 as shown in Fig. 5.

The guide sleeve 12 is simply cut in the desired length from tubular stock. After the plates 14 have been rigidly joined, the precut sleeve 12 is inserted with a snug fit through the aligned openings 15. Preferably, the lower end of the sleeve 12 is inserted just sufficiently to extend completely across the inner ends of the sockets 18, and slightly beyond the lower walls thereof, as best shown in Fig. 4. As a result, most of the sleeve 12 is disposed above and projects upwardly from the head 10. Due to the curvature of the walls 15 of the complementary protuberances 16, the peripheral edges of the openings 15 are, of course, deformed, but the stamping and drawing operation is carried out in such a manner that the edges will conform to and snugly embrace the outer peripheral surface of the sleeve 12. The sleeve 12 is rigidly secured to the head 10 as indicated at 19 by welding it to the marginal inner edge portions of the plates 14.

The supporting legs 11 may be of any suitable character, and in the present instance are of tubular construction bent into L-shaped form, with depending portions having casters 20 mounted in the lower ends and with horizontal portions adapted for connection at their inner ends to the head 10. Thus, the cylindrical end of the horizontal portion of each leg 11 is inserted with a snug fit into one of the sockets 18, and is rigidly secured therein against separation or rotation by means of a diametrical pin or rivet 21.

The axial sleeve 12 is adapted to receive the standard 13 with a snug sliding fit. In the present instance, the standard 13 is shown as a solid cylindrical rod formed along one side with a spline groove 22, and in the other side with a longitudinal series of spaced locating recesses 23. A fixed spline pin 24 is extended through one side wall of the sleeve 12 into engagement within the groove 22 to constrain the standard or post 13 against rotation. A spring actuated detent 25 is mounted on the opposite side wall of the sleeve 12, and provided with a plunger 26 adapted for selective engagement in any one of the recesses 23 to lock the post 13 adjustably in any desired vertical position.

It will be evident that I have provided a chair

base which is extremely simple and inexpensive in construction, and which, at the same time, is strong and rugged so as to provide a sturdy connection between the legs and an ample and stabilized support for the chair seat. All of the elements of the chair base can be expeditiously and inexpensively produced from ordinary stock parts, such as tubes and flat sheet material, and then joined together in a rigid unitary construction.

What I claim is:

1. A supporting base for a vertical standard comprising, in combination, two circular metal plates riveted together in flat face to face engagement to constitute a central head, each plate being preformed with a central circular opening and with a plurality of uniformly spaced semi-cylindrical protuberances struck outwardly from one side of the normal plane and extending radially from said opening to the outer periphery, said protuberances of said plates being located in registering opposed relation to define cylindrical sockets, a plurality of generally L-shaped tubular metal legs having horizontal end portions respectively extending into and pinned against rotation and endwise movement within said sockets, a tubular metal guide sleeve extending through and welded to the marginal edge portions of said openings in said plates and projecting upwardly therefrom to slidably receive a cylindrical post, means associated with said sleeve for constraining said post against rotation therein, and means associated with said sleeve for locking said post in selected position of axial adjustment therein.

2. A supporting base for a vertical standard comprising, in combination, two plates rigidly secured together in flat registering face to face

engagement to constitute a central head, each plate being formed with a central opening and with a plurality of uniformly spaced protuberances struck outwardly from one side of the normal plane and extending from said opening to the outer perimeter, said protuberances of said plates being located in opposed relation to define sockets, a plurality of legs having upper end portions extending into and rigidly secured within said sockets, and a hollow guide sleeve extending through said openings in said plates and rigidly secured thereto and projecting upwardly therefrom to slidably receive and support a vertical post.

3. A supporting base for a vertical standard comprising, in combination, two separate pre-formed metal plates rigidly secured together in flat face to face engagement to constitute a central head, said plates being formed with opposed portions to define a plurality of radial sockets spaced about the periphery, a plurality of separate pre-formed legs having upper end portions extending into and rigidly secured within said sockets, and a separate pre-formed guide sleeve opening centrally through and rigidly secured to said plates and projecting upwardly therefrom to slidably receive a vertical standard.
